(57) **CLAIM**

The ornamental design for an automotive wheel, as shown and described.

DESCRIPTION

Embodiment 1

FIG. 1 is a perspective view of an automotive wheel, showing my new design with center cap design

FIG. 2 is a front view of FIG. 1

Embodiment 2

FIG. 3 is a perspective view of an automotive wheel, showing my new design without the center cap; and,

FIG. 4 is a front view of FIG. 3.

The broken line showing of the rear portion of the wheel is included for the purpose of illustrating environment and forms no part of the claimed design.
